UNITED STATES PATENT OFFICE.

HARRISON H. TAYLOR, OF DETROIT, MICHIGAN, ASSIGNOR OF ONE-HALF
TO GEORGE THRALL, OF GROSSE ISLE, MICHIGAN.

SECTIONAL BOILER.

SPECIFICATION forming part of Letters Patent No. 606,313, dated June 28, 1898.

Application filed October 9, 1897. Serial No. 654,666. (No model.)

To all whom it may concern:

Be it known that I, HARRISON H. TAYLOR, a citizen of the United States, residing at Detroit, county of Wayne, State of Michigan, 5 have invented a certain new and useful Improvement in Sectional Boilers; and I declare the following to be a full, clear, and exact description of the invention, such as will enable others skilled in the art to which it 10 appertains to make and use the same, reference being had to the accompanying drawings, which form a part of this specification.

My invention has for its object an improved sectional boiler of novel construction and of 15 superior utility.

Among other features my invention aims to do away with large piping and malleables in the downflow-pipes, water-legs, or large manifolds to supply water to the uptakes and 20 to provide a boiler of this class which may readily be erected and repaired and whereby increased efficiency may be secured.

My invention consists of the construction, combination, and arrangement of devices hereinafter described and claimed, and illustrated 25 in the accompanying drawings, in which—

Figure 1 is a front elevation of a sectional boiler embodying my invention, the inclosing case having its front removed. Fig. 2 is a 30 longitudinal section on the line 2 2, Fig. 1. Fig. 3 is a detail view of one of the uptake-pipes. Fig. 4 is a longitudinal vertical section through one of the upper manifolds. Fig. 5 is a similar view through one of the 35 lower manifolds. Fig. 6 is a detail view of one of the couplings. Fig. 7 is a detail view of one of the pipes connecting the lower manifolds with the supply-pipe. Fig. 8 is a vertical cross-section through the steam-dome. Fig. 9 is a partial side elevation. Fig. 10 is 40 a detail view through a portion of one of the pipes C and its connection with the water-distributing pipe.

I carry out my invention as follows:

45 A is a steam-dome extending from the front to the rear of the boiler, the dome being preferably cylindrical.

At a proper distance below the dome is located a water distributing or supply pipe B, 50 the upper portion running parallel with the dome and united thereto by a series of ver-

tical tubes C. These tubes convey water from the dome down to the distributing-pipe B.

A' is the steam-pipe leading from the dome.

B' is the water-column, communicating, 55 preferably, with the front leg of the distributing-pipe, the front leg extending downward, as shown at B², at the front of the boiler, and provided with a valve, as shown at B³.

B⁴ is the gage.

B⁵ is the inflow-leg of the distributing-pipe, preferably located at the rear of the boiler.

D is the grate; D', the combustion-chamber; D², the case.

Near its top the dome is provided with two 65 rows of holes (indicated at a and a') to receive a corresponding series of connecting-pipes E and E', entering the dome on the two sides thereof through said holes. These holes extend at suitable intervals from end to end 70 of the dome.

F and F' denote two series of lower manifolds, one series extending from each side of the distributing-pipe, as shown, at a downward incline, the manifolds of each series preferably located closely side by side and each manifold of each set united to the distributing-pipe B by a connecting-nipple G, said nipples G having right and left hand screw-threaded connections with the corresponding 80 manifold and with the distributing-pipe, respectively, and being of narrower diameter than the manifold. These nipples G may thus obviously be readily screwed into place to connect the manifolds and the distributing-pipe by any suitable wrench. 85

H and H' denote a series of upper manifolds parallel with the lower manifolds and connected therewith, respectively, by a series of uptake pipes or tubes J. These latter tubes 90 J, I construct with enlarged threaded upper ends, as shown at j, to engage corresponding threaded orifices h in the upper manifolds through the lower side thereof. Similar orifices h' are formed also in the upper side of 95 the manifold, registering with the orifices h. The lower ends of the pipes J are of the same diameter as the pipe and have a threaded engagement in orifices f of the lower manifolds.

It will be seen that the upper manifold is 100 constructed with orifices h and h' of sufficient diameter to allow the lower ends of the pipes

J to be passed therethrough, whereby the said pipes may readily be located and secured in place, the two ends being threaded into the corresponding upper and lower manifolds.

- 5 The upper manifolds are provided with plugs h^2 , engaged in the upper side thereof to close the orifices h' after the pipes J are in place. The outer extremities of the upper and lower manifolds are also provided with plugs h^3 , 10 having a threaded engagement therewith, whereby the manifolds may readily be cleaned. The upper manifolds are connected with the pipes E and E', respectively, by series of pipes K, connecting-nipples K', intervening 15 between the manifolds and the pipes K, unions or T's K² connecting the pipes K and nipples K'. The pipes K are preferably arranged in sets of two pipes each, each alternate set being raised above the adjacent sets 20 of pipes to permit a ready engagement of the pipes with a wrench to engage the pipes in place. I prefer, also, to employ Y-shaped couplings (indicated at L) to unite two of the pipes K or a set of said pipes with a single 25 pipe E or E', thereby diminishing the number of pipes entering the dome. The pipes K are set at an angle parallel with the manifolds. The pipes J and the pipes E and E' on corresponding sides of the dome are also parallel, the pipes J on the two sides extending 30 upward at divergent angles.

It is obvious that an upper and a corresponding lower manifold connected by the uptake-pipes J form a section connected to 35 the distributing-pipe by the right and left threaded nipple G, while the section is connected to the unions K² by the corresponding and similarly-constructed nipple K'. It will be seen, therefore, that each section can readily 40 be taken out if repairs are necessary by simply disconnecting the corresponding nipples G and K'. Every section is thus independent of the other sections, so that each may contract and expand independently of 45 the other. The sections may be removed either by making the top of the case D² removable or by taking out the grate the sections may be taken out through the fire-door.

It will be obvious that the water entering 50 the distributing-pipe B passes thence into the lower manifolds F and F' and thence into the uptakes J. The location and arrangement of the sections in the combustion-chamber are such that the heat may pass about and around 55 and between the uptakes and under and over the lower manifolds and about the steam-drum, as well as about the upper manifolds, and the pipes connecting the upper manifolds with the dome in a most effectual and thorough manner.

The steam generated in the uptakes J passes into the dome, while any water in the pipes J will fall back into the base thereof and into the lower manifolds, the water being held 60 therein. Water of condensation in the steam-dome will obviously flow down through the tubes C into the distributing-pipe. The tubes

J, connecting the top and bottom manifolds, are preferably steel tubes. All the threads in the top and bottom manifolds and on the tubes J are right-hand threads. The tubes, being smaller than the orifices h and h' in the upper manifolds, may be readily passed therethrough, so that the threads on each end of said pipes or tubes may be screwed home at 75 the same time by any suitable instrument, as an ordinary pipe-wrench. When the individual sections have been thus put together, they are ready to be connected with the dome and with the water-distributing pipe in the 80 manner above described. The lower manifolds, being connected closely together, form a solid crown-sheet over the fire by which the products of combustion are diverted and compelled to pass to either side of the sections, 85 outward around the outer ends of the lower manifolds, then inward through the tubes J against and about the dome, thence upward through the pipes connecting the upper manifolds with the dome, and thence up the smoke-stack D³. The upper manifolds are also placed close together, thereby preventing the products of combustion passing therethrough and forming a flue between the manifolds. The water-legs B² and B⁵ form sediment- 95 pockets and also support the boiler. They may be provided with any suitable fittings at the bottom for bolting down, as indicated at B⁶. The casing may be constructed in any desired manner, preferably of sheet-steel and fire-felt, and may be bolted or secured to the upper manifolds in any suitable way.

I prefer to connect the pipes C with the water-distributing pipe, as illustrated more particularly in Fig. 10, employing a jam-nut 105 O upon the pipes C, with an intervening packing-ring M', preferably made of soft metal. When the nut is run forcibly down upon the packing-ring, the joint will be made steam-tight. Below the adjacent ends of the pipes E E' within the steam-dome I prefer also to locate a shield R, which may be secured intermediate its ends to the dome in any suitable manner, as by rivets at r, the shield extending downward in both directions a sufficient 110 distance to direct the steam toward the lower portion of the dome, as shown more particularly in Fig. 8, the arrows showing the direction of the products of combustion.

The orifices in the pipe B to receive the 115 nipples G are shown at G'.

The steam-pipe A' preferably runs the whole length of the steam-dome therewithin, the same being shown broken off in Fig. 2 intermediate its ends in order to disclose other parts of the construction. The same is shown in cross-section in Fig. 8 and is preferably provided with orifices (indicated at a⁵) on the upper side thereof, suitably distributed for the entrance of steam thereinto.

What I claim as my invention is—

1. In a boiler, the combination of a steam-dome, a water-distributing pipe located therebeneath and communicating therewith, and

a series of steam-generating sections on opposite sides thereof connected at the base with the water-distributing pipe, and at the top with the steam-dome, the sections on opposite sides of the dome and pipe diverging at their upper ends, substantially as set forth.

2. In a boiler, the combination of a steam-dome, a water-distributing pipe located under the longitudinal center of the dome, and a series of sections on opposite sides thereof each consisting of a lower manifold and an upper manifold united by vertical uptake-pipes, each of said lower manifolds outwardly and downwardly inclined from the water-distributing pipe and connected therewith, and each of the upper manifolds similarly inclined and connected with the steam-dome, the outer extremities of said manifolds diverging on opposite sides of the dome and pipe, substantially as set forth.

3. In a boiler, the combination of a steam-dome, a water-distributing pipe, a series of vertical pipes connecting the distributing-pipe and dome, and a series of independent steam-generating sections on opposite sides thereof connected at the base with the distributing-pipe, and at the upper end thereof connected with the steam-dome, each of said sections constructed with a lower and with an upper manifold, said manifolds connected by uptake-pipes, outwardly diverging on opposite sides of the dome, substantially as set forth.

4. In a boiler, the combination of a steam-dome, a water-distributing pipe parallel therewith and therebeneath, a series of pipes connecting the distributing-pipe with the bottom of the dome, and boiler-sections outwardly diverging at their upper ends on opposite sides of the dome, said sections connected at their base with the distributing-pipe and at their upper ends with the dome, substantially as set forth.

5. In a boiler, the combination of an elongated steam-dome, an elongated distributing-pipe extending longitudinally of the dome and therebeneath, a series of pipes connecting the distributing-pipe with the base of the dome, a series of lower manifolds extending at a downward and outward incline on each side the distributing-pipe and connected therewith, a series of upper manifolds on each side the dome parallel with the lower manifolds, and a series of uptakes connecting the upper and lower manifolds, said upper manifolds connected with the steam-dome, said uptakes on opposite sides of the dome and pipe being outwardly diverging at their upper ends, substantially as set forth.

6. In a boiler, the combination of an elongated steam-dome, a water-distributing pipe underneath the dome and extending longitudinally therewith, a series of sections on opposite sides thereof constructed with upper and lower parallel manifolds connected by uptakes outwardly inclined at their upper ends on opposite sides of the dome and pipe, right and left hand threaded nipples connect-

ing the lower manifolds separately into the distributing-pipe, a series of pipes parallel with said nipples connected into the steam-dome, and a series of right and left hand threaded nipples connecting the last-named pipes into the upper manifolds, substantially as set forth.

7. In a boiler, the combination of an elongated steam-dome, an elongated water-distributing pipe, a series of connecting-pipes connecting the distributing-pipe with the base of the dome, a series of lower manifolds connected with the distributing-pipe, a series of upper manifolds connected into the steam-dome, and a series of uptake-pipes connecting each of the lower manifolds with the corresponding upper manifolds, the upper ends of the uptake-pipes having an enlarged threaded head, and the upper manifold constructed with openings to permit the passage of the lower end of the uptake-pipes therethrough to engage the lower manifold, substantially as set forth.

8. In a boiler, the combination of a steam-dome, a water-distributing pipe therebeneath, a series of pipes connecting the distributing-pipe with the dome, and a series of sectional steam-generators on opposite sides thereof communicating at their base with the distributing-pipe, and at their upper ends with the steam-dome, said sections outwardly diverging at their upper ends on opposite sides of the dome and pipe, substantially as set forth.

9. In a boiler, the combination of a steam-dome, a supporting water-distributing pipe therebeneath and communicating therewith, a series of lower manifolds communicating with the distributing-pipe and forming a crown-sheet above the grate, a series of upper manifolds, a series of pipes connecting the upper and lower manifolds, a series of pipes leading into the steam-dome, and connections uniting said latter pipes with the upper manifolds, substantially as set forth.

10. In a boiler, the combination of a steam-dome, a water-distributing pipe connected therewith, lower manifolds on opposite sides thereof connected with the distributing-pipe, upper manifolds on opposite sides of the dome and pipe connected with the dome, and uptake-pipes connecting the manifolds, the upper manifold provided with plugs on the upper side for cleaning the uptakes, said uptakes diverging at their upper ends on opposite sides of the dome and pipe, substantially as and for the purpose described.

11. In a boiler, the combination of a steam-dome, a water-distributing pipe connected therewith, lower manifolds on opposite sides thereof connected with the distributing-pipe, upper manifolds on opposite sides of the dome and pipe connected with the dome, and uptake-pipes connecting the manifolds, said uptakes diverging at their upper ends on opposite sides of the dome and pipe, said manifolds provided with plugs at one end there-

of, substantially as and for the purpose described.

12. In a boiler, the combination of a steam-dome, a water-distributing pipe connected therewith, lower manifolds on opposite sides thereof connected with the distributing-pipe, upper manifolds on opposite sides of the dome and pipe connected with the dome, and uptake-pipes connecting said manifolds, respectively, said uptakes diverging at their upper ends on opposite sides of the dome and pipe, and said lower manifolds assembled close together, substantially as and for the purpose set forth.

13. In a boiler, the combination of a steam-dome, a water-distributing pipe connected therewith, lower manifolds on opposite sides thereof connected with said pipe, upper manifolds on opposite sides of the dome and pipe connected with said dome, and uptake-pipes connecting said manifolds, the upper and lower manifolds, respectively, assembled close together forming a flue therebetween, said uptakes diverging at their upper ends on opposite sides of the dome and pipe, substantially as set forth.

14. In a boiler, the combination of a steam-dome, a water-distributing pipe connected

therewith, lower manifolds on opposite sides thereof connected with said pipe, upper manifolds on opposite sides of the dome and pipe connected with said dome, and uptake-pipes connecting said manifolds, said uptake-pipes diverging at their upper ends on opposite sides of the dome and pipe and constructed with right-hand threads at their extremities of less diameter at the bottom than at the top, whereby said uptake-pipes may be simultaneously connected with the corresponding upper and lower manifolds, substantially as set forth.

15. In a boiler, the combination of a steam-dome, a water-distributing pipe connected therewith, steam-generating sections connected at their lower ends with said pipes, and additional pipes connecting the upper ends of said sections with the steam-dome, said dome provided with an interior shield beneath the adjacent ends of the last-mentioned pipes, substantially as set forth.

In testimony whereof I sign this specification in the presence of two witnesses.

HARRISON II. TAYLOR.
